APPARATUS FOR TRANSPORTING MOLTEN MATERIALS

Filed July 1, 1936

UNITED STATES PATENT OFFICE

2,115,213

APPARATUS FOR TRANSPORTING MOLTEN MATERIALS

Spottiswoode W. Randolph, Baltimore, Md., assignor, by mesne assignments, to Koppers Company, a corporation of Delaware

Application July 1, 1936, Serial No. 88,476

5 Claims. (Cl. 105—270)

This invention relates to apparatus for the transportation of molten materials, and more particularly to vehicles for transporting molten iron and steel, known as hot metal cars.

5 Apparatus of this type is well-known and has heretofore been used in and around steel mills for transporting molten iron and steel from the furnaces to more or less distant points at which the molten metal is to be cast or otherwise used.

10 One type of vehicle so employed comprises a container for the molten metal supported by means of trunnions, at either end, in bearings mounted on railway trucks. In such vehicles the containers are tiltable for the purpose of discharging

15 their contents, tilting being effected by external means, such as a crane operated hook, or by means carried on the vehicle, such as an electric motor mounted on one of the trucks and connected, through suitable gearing, to the container.

20 The present invention relates to vehicles of the latter type, and has for an object the provision of a suitable driving connection between the electric motor or other source of power and the container, such means being employed that the container may be tilted even though it be out of alignment with the power shaft, due to inequalities in the track, sagging of the container, permanent misalignment of the parts, or for any

25 other reason. A further object is the provision of a driving connection for the described purpose, which will not be injured by misalignment of the shaft and the container, occurring by reason of the vehicle passing around curves or over inequalities in the track, or through other causes.

30 These and other objects, features and advantages will appear from the description which follows, together with the accompanying drawing, in which

35 Fig. 1 is a side elevation of one end of a vehicle of the type to which the present invention is adapted;

Fig. 2 is an end view of the vehicle of Fig. 1;

Fig. 3 is an enlarged longitudinal vertical section through the container supporting bearing and driving connection, on line 3—3 of Fig. 4;

Fig. 4 is a vertical transverse section on line 4—4 of Fig. 3; and

Fig. 5 is a horizontal section on line 5—5 of Fig. 3.

Referring to Fig. 1, a container 10, provided with a suitable charging and discharging opening 11, is provided at one end with a trunnion 12 which is supported in a bearing 13, the latter being carried by a suitable pedestal 14 mounted

on a railway truck 15. The trunnion 12 and bearing 13 are formed with spherical bearing surfaces, separated by a bushing 16 of anti-friction metal (Fig. 3). It will be understood that the opposite end of the container is tiltably supported, in a similar manner, upon another truck, which it is unnecessary to illustrate. It will also be appreciated that, if desired, the parts might be reversed, the container being provided with bearings adapted to receive trunnions mounted 10 on the railway trucks. 5

For the purpose of tilting the container 10 to discharge its contents a suitable source of power, such as a reversible electric motor 17, is provided. The motor 17 is connected by suitable reduction 15 gearing, indicated in Fig. 1, to a shaft 18, through which rotary motion is transmitted to the container 10 by means now to be described. The shaft 18 is journalled in bearings 27 and 28, carried by the gear casing 29, and is permitted substantially no end play. 20

As will be best seen in Figs. 3 and 4, the trunnion 12 is provided with a recess 19, rectangular in cross-section, the upper and lower surfaces of which are provided with liners 20 and 21 of anti-friction metal. A hollow block 22, rectangular in cross-section, is mounted within the recess 19, fitting snugly between the anti-friction liners 20 and 21. It will be perceived that the transverse dimension of the block 22 is considerably less 25 than that of the recess 19, thus permitting the block 22 a certain amount of horizontal planar movement, both linear and angular, within the recess 19. It will be understood that the term "planar movement" refers to linear or angular 30 movement in which each element of the moving member moves in a single plane, all of such planes being parallel. 35

The end of the shaft 18, modified to a rectangular cross-section, extends into, and preferably 40 entirely through, the central aperture in the block 22, fitting snugly between the vertical walls 23 and 24 thereof. The shaft 18 and block 22 are secured together by means of pins 25, 25' which are threaded into the walls 23 and 24 of the block 45 22, and extend inwardly into engagement with vertically elongated slots 26, 26' formed in the vertical surfaces of the shaft 18. The latter having a vertical dimension somewhat less than that of the central aperture of the block 22, is permitted a certain amount of vertical planar movement, both linear and angular, within the block. 50

A lubricant chamber 30 is provided between the gear casing 29 and the bearing 13, and communicates with the recess 19. The chamber 30 is 55

adapted to be supplied with a suitable quantity of lubricant, and to act as a reservoir supplying lubricant to the bearings 13 and 28, and to the members within the recess 19.

5 Since the block 22 is secured to the shaft 18, which latter is supported without substantial end play, there will be no substantial longitudinal movement of the block 22 and shaft 18 with respect to the trunnion 12. However, since the 10 block 22 is permitted a limited transverse movement within the recess 19, and the shaft 18 may have a limited vertical movement within the block 22, it is apparent that the driving connection thus formed between the shaft 18 and the 15 trunnion 12 will be operative despite such misalignment of the shaft and container as is likely to occur in service, and will not be injured by such misalignment.

20 Due to the inherently rugged nature of the elements making up the driving connection of the present invention, it is particularly well adapted to transmit the considerable torque necessary for tilting the heavy container filled with molten metal, and to withstand injury.

25 The terms and expressions employed in the foregoing specification are terms of description and not of limitation, and it is recognized that many variations of the described mechanism may be made without departing from the scope of the 30 present invention. For example, the recess 19, block 22 and shaft 18 need not be rectangular, so long as the outer surfaces of the block 22 are complementary to the inner surfaces of recess 19 and the inner surfaces of block 22 are complementary to the adjacent surfaces of the shaft 18, and so long as each member has two opposite planar surfaces for engagement with similar surfaces of the adjacent member or members. It is, of course, essential that the play of the block 40 22 within the recess 19 and the play of the shaft 18 within the block 22, be in relatively perpendicular planes.

Having thus described the invention, what is claimed as new and desired to be secured by 45 Letters Patent is:—

50 1. In a hot metal car, in combination, a pair of wheeled trucks, bearings carried by said trucks, a container trunnioned in said bearings, one of said trunnions having a central recess, a hollow member mounted within said recess for rotational and translational planar movement therein, a shaft extending into said hollow member and adapted for rotational and translational movement therein in a plane perpendicular to the plane of movement of said hollow member, said trunnion, hollow member and shaft being incapable of substantial relative rotation about the axis of said shaft, and means for rotating said shaft.

55 2. In a hot metal car, in combination, a pair

of wheeled trucks, bearings carried by said trucks, a container trunnioned in said bearings, one of said trunnions having a central recess, a hollow member mounted within said recess for rotational and translational transverse movement therein, 5 a shaft extending into said hollow member and adapted for rotational and translational vertical movement therein, said trunnion, hollow member and shaft being incapable of substantial relative rotation about the axis of said shaft, and means 10 for rotating said shaft.

3. In a hot metal car, in combination, a pair of wheeled trucks, bearings carried by said trucks, a container trunnioned in said bearings, one of said trunnions having a central rectangular recess, 15 a hollow rectangular member mounted within said recess for rotational and translational planar movement therein, a shaft having a portion of rectangular cross-section, said rectangular portion extending into said hollow member and 20 adapted for rotational and translational movement therein in a plane perpendicular to the plane of movement of said hollow member, said trunnion, hollow member and shaft being incapable of substantial relative rotation about the 25 axis of said shaft, and means for rotating said shaft.

4. In a hot metal car, in combination, a pair of wheeled trucks, bearings carried by said trucks, a container trunnioned in said bearings, one of 30 said trunnions having a central recess, a hollow member mounted within said recess for rotational and translational planar movement therein, a shaft extending into said hollow member and secured thereto for rotational and translational 35 movement therein in a plane perpendicular to the plane of movement of said hollow member, said trunnion, hollow member and shaft being incapable of substantial relative rotation about the axis of said shaft, and means for rotating said 40 shaft.

5. In a hot metal car, in combination, a pair of wheeled trucks, bearings carried by said trucks, a container trunnioned in said bearings, one of 45 said trunnions having a central recess rectangular in cross-section, a hollow rectangular member mounted within said recess for rotational and translational planar movement therein, a shaft having a portion of rectangular cross-section, said rectangular portion extending into said hollow 50 member and secured thereto for rotational and translational movement therein in a plane perpendicular to the plane of movement of said hollow member, said trunnion, hollow member and shaft being incapable of substantial relative 55 rotation about the axis of said shaft, and means for rotating said shaft.

S. W. RANDOLPH.
